SMOKE BOX STRUCTURE FOR LOCOMOTIVES

Filed Dec. 31, 1931

3 Sheets-Sheet 3

The image contains three technical drawings of a window frame assembly, labeled Fig. 3, Fig. 4, and Fig. 5.

Fig. 3: A side cross-sectional view of a window frame. The frame is labeled 4. Inside the frame, a glass pane is labeled 6. A small rectangular component with a circular hole is labeled 9. A vertical strip of material is labeled 7. A horizontal strip of material is labeled 10. A bracket labeled 11 is attached to the frame. A small detail labeled 5 is shown at the bottom left.

Fig. 4: A top-down view of the window frame. It shows the glass pane 6 and the horizontal strip 10. A bracket labeled 11 is attached to the frame. A small detail labeled 5a is shown at the bottom left.

Fig. 5: A side cross-sectional view of the window frame, similar to Fig. 3, showing the internal structure and components.

SMOKE BOX STRUCTURE FOR
LOCOMOTIVESThomas E. Cannon, Pittsburgh, and Charles F.
Krauss, Ambler, Pa.

Application December 31, 1931, Serial No. 584,254

5 Claims. (Cl. 105—37)

The object of our invention is to construct the smoke-box of a locomotive so that a pocket will be formed in one side thereof, into which can be placed an air-pump or other piece of machinery connected to the locomotive, so as to provide a view for the engine crew which will not be obstructed by an air-pump or other piece of machinery projecting laterally from the locomotive at the smoke-box.

10 In the accompanying drawings:

Fig. 1 is a transverse sectional view through a smoke-box illustrating our invention;

Fig. 2 is a side view of the smoke-box, showing the pocket or recess, and illustrating an air-pump in dotted lines secured in said recess;

15 Fig. 3 is a detached perspective view of the shell forming the pocket;

Fig. 4 illustrates a modification in which the pocket is formed in an integral cast steel casing of the smoke-box; and

20 Fig. 5 is another modification showing the shell which forms the pocket secured to the casing by a welded butt-joint.

1 The smoke-box casing of a locomotive, cut away at one side as at 2. 3 is the shell of a pocket, shaped as shown in Fig. 3. The depth of this pocket is sufficient to allow an air pump "A" or other piece of machinery to be secured therein, so as to be substantially flush with the outer portion of the shell of the locomotive or the lagging of

25 the boiler. The shell has an upper flange 4 which laps over the casing 1 of the smoke-box above the opening 2 and also has a flange 5 at the lower end, which overlaps the casing 1 of the smoke-box below the opening 2, and at each side of the shell are flanges 6—6, which overlap the casing at each side of the opening 2. These flanges are connected so as to form a continuous flange which overlaps the casing, and the upper portion

30 of the shell is preferably in the form of an arc, although it may be of any shape desired. The back 7 of the shell is preferably vertical and the upper end of the shell is inclined as at 8. Formed integral with the back 7 are lugs 9 located a considerable distance above the bottom of the shell, and lugs 10 are formed on a depending portion 11

35 of the shell, as clearly shown in Fig. 1. These lugs have threaded openings therein for the reception of the bolts 12 which secure the air-pump "A" firmly to the shell. The shell is of sufficient thickness and rigidity to rigidly support the air-pump. If mechanisms other than air-pumps are to be secured in the pocket "X" formed by the shell, the lugs may be placed in such position

40 as to provide means for firmly securing the mech-

anism within the pocket and to the shell. The flanges 4, 5 and 6 are preferably welded to the casing at 13, the weld extending entirely around the flanged portion of the shell, but it will be understood that the flanges 4, 5 and 6 may be riveted to the casing or may be riveted and welded without departing from the essential features of the invention.

The shell in the present instance is preferably made as an integral steel casting, and, being made in one piece, it reinforces the casing of the smoke-box and it does not project a sufficient distance into the smoke-box to interfere with the mechanisms of the locomotive located in the smoke-box. The shell may also in some instances provide a means for firmly attaching such mechanisms firmly in the smoke-box by casting lugs 9a at the back of the shell, as shown in Fig. 1 and securing them to the lugs.

In some instances the pocket may be formed integral with the shell of the smoke-box as shown in Fig. 4, and instead of the shell having flanges which overlap the casing of the smoke-box, the shell may have portions 5a which abut against the casing 1a as shown in Fig. 5 and the two parts may be welded together.

We claim:

1. The combination of a casing of the smoke-box of a locomotive having an opening in one side thereof; a shell located in said opening and depressed to form a pocket therein, the shell having a substantially vertical back portion the upper part of which extends outwardly at an angle of approximately 45° forming a partial cover for an accessory located within the pocket and secured to the back portion of the shell.

2. The combination of a casing of a smoke-box of a locomotive, having an opening in one side thereof; an integral cast shell located in the opening, being depressed to form a pocket, the shell having a flange extending around the pocket and welded to the casing, said shell having a depending portion at the bottom; lugs on the depending portion to which an air-pump can be secured; and lugs projecting into the pocket from the back of the shell, to which an accessory can be secured.

3. A smoke-box for a locomotive, having a pocket in the side thereof for reception of a locomotive accessory, the upper end of said pocket extending outwardly over and forming a partial covering for said accessory.

4. A smoke-box for a locomotive, having a pocket in the side thereof for reception of a locomotive accessory, the upper end of said pocket

extending outwardly over and forming a partial covering for said accessory, and means on the upright wall of said pocket for attaching the accessory.

5. A smoke-box for a locomotive, having a pocket in the side thereof for reception of a locomotive accessory, the upper end of said pocket extending outwardly over and forming a partial

covering for said accessory, and means on the upright wall of the pocket for attaching the accessory including a depending portion and a lip for supporting a portion of the weight of said accessory.
